Attys.

UNITED STATES PATENT OFFICE

RALPH L. LOOMIS, OF BEDFORD, MASSACHUSETTS

INTERMITTENTLY-OPERATING TORQUE-TRANSMITTING MECHANISM

Application filed March 18, 1929. Serial No. 347,829.

This invention relates to mechanism for intermittently transmitting torque from a motor to a feed roll which may be a member of a pair of rolls, the nip of which engages a sheet or other material to progressively feed the same.

An object of the invention is to provide an improved torque-transmitting mechanism adapted to alternately impart to the rolls a feeding movement of predetermined amplitude, and prevent such feeding movement for a predetermined period.

Another object is to cause, for a purpose hereinafter stated, a slight reverse movement of the feed roll while its feeding movement is prevented.

Another object is to enable the amplitude of the feeding movement of the roll to be conveniently varied.

Of the accompanying drawings forming a part of this specification,—

Figure 1 is a side view of my improved feeding mechanism associated with a pair of feed rolls adapted to feed sheet material, and means for acting on said material when it is at rest, said means being, in this instance, adapted to sever the material, the feeding mechanism being shown as it appears when imparting a feeding movement to the feed rolls.

Figure 2 is a view similar to Figure 1, showing the mechanism as it appears when the feeding movement is arrested.

Figure 3 is a view similar to Figure 2, illustrating the slight reverse movement of the feed rolls.

Figure 4 is a section on line 4—4 of Figure 1.

Figure 5 is a section on line 5—5 of Figure 1.

Figure 6 is a section on line 6—6 of Figure 5.

The same reference characters indicate the same parts in all of the figures.

My improved mechanism is adapted to intermittently transmit torque from a source of power such as an electric motor, to a feed roll 13, which may be a member of a pair of coacting feed rolls 13 and 14, adapted, in this instance, to feed sheet material 15, such

as paper, engaged by the nip of the rolls. The shaft 16 of the roll 13 is journaled in fixed bearings 17, one of which is shown by Figure 4. The shaft 18 of the roll 14 may be vertically movable in a bearing 19, and held down by springs 20, one of which is shown by Figure 4. Said bearings may be supported by any suitable frame work, designated in part by 21.

Figures 1, 2 and 3 show means for acting on the material 15, when the latter is at rest, said means including, in this instance, a reciprocating severing blade 22, and a fixed blade 23, cooperating therewith. The acting means may be, however, otherwise embodied and adapted to otherwise act on the material 15, for example, to emboss or otherwise ornament the material, with or without severing it, the action on the material occurring when the latter is at rest.

When the feed rolls are organized as above described, the roll 13 is positively rotated by the mechanism next described, the roll 14 being rotated by frictional contact with the material 15, when the roll 13 rotated.

26 designates a continuously driven primary gear whose shaft 27, shown by dotted lines in Figure 1, is journaled in a fixed bearing in a standard 28. The primary gear 26 may be driven by a motor connected directly to its shaft 27. I prefer, however, to drive the primary gear by a motor shaft 12, having a relatively small gear 25 meshing with the primary gear. 29 designates an orbital gear, so called because it revolves in an orbit around the axis of the primary gear 26, without rotating on its own center, so that its motion is not planetary. The orbital gear is fixed eccentrically to the primary gear 26 by holding means, preferably embodied as best shown by Figure 5, and hereinafter described, said holding means preventing rotation of the gear 29 on its own center and maintaining the said center at one side of the axis of the primary gear 26.

30 designates a shiftable secondary gear meshing with the orbital gear 29 and with a gear 31, fixed by a key 32 (Figure 4) to the feed-roll shaft 16.

A jointed connection is provided between 100

the shaft 16 and the center of the orbital gear 29. Said connection includes an arm 33, preferably made in two parts, as shown by Figure 4, adapted to oscillate on the shaft 16, and a link 34 connected at one end by a pivot stud or bolt 35, with the swinging end of the arm 33, and at the other end with the center of the orbital gear 29, as described later. Said connection maintains the secondary gear in engagement with the orbital gear and the feed-roll gear and permits the secondary gear to be oscillated by the orbital movement of the gear 29.

The orbital gear is preferably radially adjustable toward and from the axis of the primary gear 26, to permit variations of the diameter of its orbit, and corresponding variations of the amplitude of the feeding movement of the feed roll 13. To this end, I attach to the primary gear, as by bolts 37, a guide 36, having a slot 38 extending radially from the primary gear shaft 27. A slide 39 is movable in the slot 38 and provided with a laterally projecting stud 40, entering the hub of the orbital gear 29, and fixed thereto by a key 41. The slide is longitudinally adjustable in the slot 38, to vary the radial distance of the orbital gear center from the axis of the primary gear 26, and thereby vary the amplitude of the feed movement of the roll. To hold the slide 29 in any position to which it may be adjusted, I provide bearing screws 42, engaged with tapped orifices in the guide 36, and bearing on the ends of the slide. The pivotal connection between the oscillatory arm 33 and the link 34 is also adjustable, the link being provided with a slot 43 in which the pivot stud or bolt 35 is laterally movable, said bolt being provided with a confining nut 44.

The continuous movement of the primary gear 26 and of the orbital gear 29 is in the direction indicated by arrow α in Figures 1, 2 and 3, and causes continuous changes of the relations of the moving parts to each other. Several different relations are illustrated by Figures 1, 2 and 3. When said parts are in any relation to each other except the relation shown by Figures 2 and 3, the secondary gear is rotated in the forward direction indicated by arrow y , and correspondingly rotates the feed roll. When the parts are related as shown by Figure 2, showing what I call the dead center relation, the forward rotation of the secondary gear 30, and the feeding movement of the feed roll cease briefly until the parts are related as shown by Figure 3.

During the movement of the parts from Figure 2 to Figure 3 relation, the secondary gear 30 is briefly rotated backward, as indicated by arrow z in Figure 3, and briefly rotates the feed roll backward, the object being to slightly withdraw the forward end of the material 15 from the path of the acting mem-

ber 22, as shown by Figure 3, said member being a reciprocating cutter. This withdrawal is very slight, and prevents the forward end of the material from being lifted by frictional contact with the knife when the latter is rising. The backward rotation of the secondary gear and the feed roll ceases, and forward rotation thereof is resumed, after the brief backward rotation of the secondary gear and the feed roll.

It will now be seen that during the major portion of a complete rotation of the primary gear, a feeding movement is imparted to the feed roll, and that during a minor portion of said rotation a feeding movement of the feed roll is prevented and a slight backward rotation of the feed roll is caused.

The orbital gear 29, the link 34, and the oscillatory arm 33, constitute the best embodiment at present known by me of a connection between a continuously driven primary gear and a secondary gear engaged with a feed roll, said connection being organized to impart a feeding movement to the secondary gear and the feed roll during the major portion of a complete rotation of the primary gear, and to prevent said feeding movement during a minor portion of said complete rotation.

I claim:

1. Intermittently acting torque-transmitting mechanism comprising a continuously driven primary gear, a secondary gear engaged with a feed roll to rotate the same, an orbital gear, holding means fixed to the primary and orbital gears, and holding the orbital gear in an eccentric position on the primary gear, so that the orbital gear is revolved about the axis of the primary gear without rotation on its own center, a shiftable secondary gear meshing with the orbital gear and engaged with a feed roll to rotate the latter, and a jointed connection between the center of the orbital gear, the axis of the secondary gear and the axis of the feed roll, whereby the secondary gear is maintained in engagement with the orbital gear and with the feed roll, and permitted to oscillate while rotating, said connection including an arm oscillatable on the feed roll axis, and a link pivotally connected to the swinging end of said arm and to the said holding means, the arrangement being such that the orbital gear, in moving through the major portion of its orbit, rotates the secondary gear to cause a feeding movement of the feed roll, and when moving through a minor portion of its orbit, holds the secondary gear to prevent a feeding movement of the roll and cause a slight reverse rotation of the primary gear and the feed roll.

2. Intermittently acting torque-transmitting mechanism as specified in claim 1, said holding means being adjustable to vary the radial distance of the orbital gear center from the axis of the primary gear, and thereby

vary the amplitude of rotation of the feed roll, the pivotal connection between said oscillating arm and link being also adjustable.

3. Intermittently acting torque-transmitting mechanism as specified in claim 1, said holding means comprising a slotted guide fixed to the primary gear and extending radially from the axis thereof, a slide movable in said guide and provided with a laterally projecting stud to which the orbital gear is fixed, and adjusting screws engaged with the guide and bearing on opposite ends of the slide.

In testimony whereof I have affixed my
signature.

RALPH L. LOOMIS.
